UNITED STATES PATENT OFFICE.

CHARLES W. COLLINS, OF SEATTLE, WASHINGTON.

CLOTHES-DRYING MACHINE.

1,427,580.

Specification of Letters Patent. Patented Aug. 29, 1922.

Application filed February 14, 1922. Serial No. 536,528.

To all whom it may concern:

Be it known that I, CHARLES W. COLLINS, a citizen of the United States, residing at Seattle, in the county of King and State of Washington, have invented certain new and useful Improvements in Clothes-Drying Machines, of which the following is a specification.

This invention relates to clothes drying machines.

The object of the present invention is the provision of a drier having fewer parts, more compactly constructed and which is peculiarly efficient in operation.

Other objects and advantages of the invention will appear in the following specification.

The invention consists in the novel construction, arrangement and combination of parts hereinafter described and claimed.

In the accompanying drawings,—

Figure 1 is a transverse vertical section of a clothes drying machine embodying my invention, said section being taken through 1—1 of Fig. 4. Fig. 2 is similar view with the dampers arranged to produce a circulation of air different than that attained with the dampers arranged as shown in Fig. 1. Fig. 3 is a side elevation of the drying machine. Fig. 4 is a horizontal section taken substantially through 4—4 of Fig. 1.

In carrying out the present invention, I provide a casing 5 which is divided by partitions 6, 7, 8 and 9, as shown in Figs. 1 and 35 2, into compartments 10, 11, 12 and 13, respectively.

The compartment 10 which serves as a housing for a rotary drum 14 is of a general circular shape with an inlet opening 15 at 40 the top which communicates through a chamber 16 with the outlets 11¹ and 12¹ of the compartments 11 and 12.

The compartment 12 serves as a housing for a steam heating coil 17. The compartment 11 serves as a duct for the supply of unheated air to the chamber 16 from the compartment 13 in which is provided a power driven fan 18.

A damper 20 is provided to close the outlet of the compartment 12, and a damper 19 is employed to close either of the inlet openings 11² and 12² of the compartments 11 and 12.

21 represents an opening provided in an end wall of the fan compartment for the admission thereinto of fresh air from the ex-

ternal atmosphere. 22 represents a damper provided in the opening 21.

In the wall of an exhaust chamber 23, provided in front of the fan compartment 13, is a discharge opening 24 which may be unprovided with a valve or damper.

The compartment 10 for said drum communicates through passages 25 and 26 respectively with the fan compartment 13 and the exhaust chamber 23.

A damper 27 serves to individually close either of the passages 25 or 26 as may be required in the operation of the machine. As shown, the damper 27 is in the nature of an imperforate plate pivotally connected, as at 27¹ intermediate its width.

Secured to and extending rectangularly from the damper 27 is a screen 28 of wire gauze, or an equivalent, which is adapted to be brought, alternately with the damper wings 27² and 27³, into juxtaposition with ledges 29 and 30 of the casing structure.

As illustrated in Figs. 3 and 4, the damper 22 is mounted upon a spindle 31 provided with a toothed pinion 32 in mesh with a rack bar 33 which is guided for vertical movements in casing attachments 34.

The upper end of the bar 33 is connected by a link 35 with an arm 36 provided on the spindle 19¹ of the damper 19 and, at its lower end, said bar is operatively connected to an arm 37 provided on the spindle 20¹ of the damper 20.

The spindle 20¹ is also provided with a second arm 20² which is connected by a link 37¹ to an arm 38 provided on the damper spindle 27⁴.

The arm 38, in turn, is connected as by a link 39 with means such, for example, as a handle-arm 40 whereby the screen 28 and all of the aforesaid dampers are, by preference, simultaneously operated.

The connections between the several dampers are arranged to cause the damper 22 to close the air inlet 21 when the dampers 19, 20 and 27 occupy the positions in which they are represented in Fig. 1, and to have the damper 22 in its open position with respect to the inlet 21 when the dampers 19, 20 and 27 occupy the positions in which they are represented in Fig. 2.

The drum 14, for the reception of clothes which are to be dried, has its peripheral wall formed of wire mesh or an equivalent whereby air may pass diametrically, or nearly so, through the drum in travelling between

chamber 16 and either of the passages 25 or 26 which respectively lead into the pump compartment 13 and the exhaust chamber 23.

The operation of the invention may be explained as follows: Assuming the damper 22 is in its closed position with respect to air inlet opening 21 and the screen 28 and dampers 20, 19 and 27 are disposed as shown in Fig. 1, the fan will thereupon serve to effect the circulation of air through the compartment 12, to become heated by the coils 17 therein, thence through chamber 16, drum 14, passage 25, and screen 28 back to the fan 18.

In thus passing through the screen, the latter serves to collect on one side thereof the lint taken from the clothes within the drum. After the air for a desired length of time has been circulated in the above described course, the attendant regulates the screen 28 and the dampers 22, 20, 19 and 27 to be in the positions in which they are shown in Figs. 2, 3 and 4, whereupon the fan serves to cause fresh air entering the opening 21 to be delivered through duct 11, chamber 16, drum 14, and screen 28 into the exhaust chamber 23 to escape through outlet 24.

It is to be noted that the screen 28 when in its Fig. 2 position extends across the passage 26 and when in its Fig. 1 position it extends across the passage 25 and the air in passing through the screen flows in opposite directions when traveling through the respective passages.

The damper 27 serves to close the passage 26 when the screen is positioned across the passage 25, or vice versa, thereby directing the air through the screen to receive lint upon the latter when the hot air is circulated and to liberate the lint from the screen by a current or currents of fresh air passing therethrough to the exhaust chamber 23.

It is also to be noted that the fan serves to drive the air through the heating compartment 12 and duct 11 alternately, and when the duct 11 is utilized the dampers 20 and 19 serve to exclude a flow of air through the compartment 12 thereby conserving the heat while the goods being dried are being ventilated, so to speak, by currents of relatively cool fresh air taken from the atmosphere.

What I claim, is,—

1. In a clothes drying machine, a casing having a heating chamber, a coil therein, a drying chamber communicating with said heating chamber and an exhaust connection, a fan, a chamber therefor, the last named chamber having suction connections with the space within said drying chamber and also with the atmosphere outside of the casing, a duct connecting the fan chamber with said drying chamber, and draft regulating means whereby the fan is rendered operative

to deliver air through said heating chamber or through said duct selectively to the drying chamber.

2. In a clothes drying machine, comprising a casing having a drying chamber, a power driven fan, a chamber provided for said fan within the casing, two air delivery passages extending from the fan chamber to the drying chamber, an air heating coil provided in one of said passages, said drying chamber having an exhaust passage and a passage for the return of air to the fan chamber, and regulating means for said passages whereby said fan serves to drive air through the drying chamber and selectively through the medium of the air delivery passage containing said coil and through the return passage, or through the air delivery passage which is unprovided with a coil and said exhaust passage.

3. In a clothes drying machine, a casing having air inlet and outlet openings, a rotary clothes containing drum, an air heating coil, a chamber therefor, a power driven fan for supplying air to said drum for drying the contents thereof, manually controlled means provided within the casing whereby said fan may be employed selectively to cause the circulation of the air in the casing and including said chamber or through said drum and between said casing openings exclusive of the chamber.

4. In a clothes drying machine, a casing provided with air inlet and outlet openings, a rotary drum for the reception of articles to be dried, a rotary fan, a chamber therefor, said inlet opening communicating with said chamber, passages extending from said drum to said chamber and outlet respectively, a screen and a damper adapted to be used alternately in said passages, passages extending from said chamber to a space provided in the casing above the drum, air heating means provided in one of the last named passages, and damper means provided for the last named passages whereby fan impelled air from said chamber is caused to pass through either one of such passages to the said space.

5. In a clothes drying machine having a casing provided with a drying chamber, an air heating chamber communicatively connected at its upper end with said drying chamber, a fan chamber having an inlet for the admission of air from the atmosphere exteriorly of the machine, a passage extending from said drying chamber to said fan chamber, an exhaust passage extending from said drying chamber, an outlet connection between said fan chamber and the lower portion of said heating chamber, and an air duct extending from said fan chamber and communicating with the upper portion of said drying chamber, of a power driven fan provided in said fan chamber, means

to heat said heating chamber, a screen arranged to be used in reverse positions alternately in the respective passages, and damper devices provided in the casing and 5 adapted to cooperate with said screen whereby the fan will serve to effect the admission of air selectively from outside of the casing and thence pass successively through said duct, and drying chamber, to escape through said exhaust passage, or to exclude air from the outside of the casing and thence pass successively through said duct, drying chamber and 10 screen to escape through said exhaust passage, or to exclude air from the outside of the casing and cause the air contained therein to circulate successively through the heating chamber, the drying chamber, the 15 screen, and the fan chamber.

6. In a clothes drying machine having a casing provided with a drying chamber, an air heating chamber communicatively connected at its upper end with said drying 20 chamber, a fan chamber having an inlet for the admission of air from the atmosphere exteriorly of the machine, a passage extending from said drying chamber to said fan chamber, an exhaust passage extending from 25 said drying chamber, an outlet connection between said fan chamber and the lower portion of said heating chamber, and an air duct extending from said fan chamber and communicating with the upper portion 30 of said drying chamber, of a power driven fan provided in said fan chamber, means to heat said heating chamber, and damper devices provided in the casing and adapted to direct the flow of air within the machine

whereby the fan will serve to effect the admission of air selectively from outside of the casing and thence pass successively through said duct, and drying chamber, to escape through said exhaust passage, or to exclude air from the outside of the casing 40 and cause the air contained therein to circulate successively through the heating chamber, the drying chamber, and the fan chamber.

7. In a clothes drying machine, the combination with a casing provided with partitions to afford a drum chamber, a fan chamber, an exhaust passage, a space above the drum chamber, a passageway affording communication between the fan chamber and 45 the space above the drum chamber, air heating means provided in said passageway, and a passage leading from said drum chamber to the fan chamber, of a clothes receiving drum provided in the drum chamber, a fan 50 provided in the fan chamber, manually regulated means for effecting the circulation of air within the casing to pass through said chambers and said passageway, and a screen 55 arranged to be used alternately and in reversed positions in the respective passages.

Signed at Seattle, Washington, this 3rd day of February, 1922.

CHARLES W. COLLINS.
